AMOS P. STEINER AND HAROLD E. BALSIGER, OF WAYNESBORO, PENNSYLVANIA, AS-
SIGNORS TO LANDIS TOOL COMPANY, OF WAYNESBORO, PENNSYLVANIA, A COR-
PORATION OF PENNSYLVANIA

HYDRAULIC BACK REST FOR GRINDING MACHINES

Application filed October 21, 1926. Serial No. 143,248.

Our said invention relates to a combined back-rest and work support for grinding machines and more particularly to crank shaft grinders and an object is to force the supporting blocks against the work hydraulically and also withdraw the blocks from the work hydraulically out of reach of the farthest throw of the crank-shaft, during the operation of indexing. Another object is to provide means for operating the slide at such a reduced rate that no vibration will be produced when said slide comes up against the stops although the slide is operated by fluid taken from the high pressure fluid lines which operate other mechanism of the grinding machine. Another object is to provide simple means for reversing the movement of the slide. Still further objects are to provide means for adjusting the jaws as the work progresses and to also provide means for holding the jaws firmly against the work during the grinding operation.

Referring to the accompanying drawings which are made a part hereof and on which similar numerals designate like parts in the several views,

Figure 1 is a detail side elevation of our device showing portions of the grinding machine,

Figure 2, a front elevation thereof,

Figure 3, a detail horizontal section on the line 3—3 of Figure 2,

Figure 4, a front elevation showing the arrangement of the piping,

Figure 5, a side elevation of the same,

Figure 6, a detail of a small-bore nipple used in the pressure line,

Figure 7, a plan view of the slide,

Figure 8, an end elevation of the jaw carried by the slide, and

Figure 9, a side elevation thereof detached.

Figure 10 is a detail partly in section showing the rack and pinion drive for the work support slide, Figure 11 is a detail view partly in section of the fluid pressure cylinder for actuating the work support.

In the drawings, the numeral 15 denotes the bed of the grinding machine, 16 is a bracket bolted to said bed and 17 is the base of the back-rest which is secured to said

bracket 16. The work 18 is supported in the usual manner to be operated upon by the wheel 19 shown in Figure 1. The base 17 is provided on its upper surface with slideways 20 adapted to receive a slide 21 which carries on one end the back-rest jaw 22 adjustably mounted in slide 21. Threaded into the opposite end of the slide 21 is an adjusting screw 23 having mounted thereon a stop-dog 24 adapted to coact with a stop 25. The inner end 26 of this screw 23 is rounded off and bears against the rear portion 27 of the jaw 22 to force it against the work. The work is supported against downward movement by means of a jaw 28 mounted on a lever 29 pivoted between ears 30 formed on the base 17 and having a depending lug 31 which rests against the end of an adjusting screw 32 threaded into a slidable bushing 33 in the base 17. The screw 32 carries a stop-dog 34 which coacts with a stop 35 accurately adjusting the jaw 28. The slide 21 with its associated parts and the bushing 33 with the screw 32 are moved in unison by means of a bracket 36 bolted to the under side of the slide 21 and secured to the end of the bushing 33. The jaw 22 is removed from the work by means of the slide 21 through a spring 37 having one end secured to a pin 38 on the slide and its opposite end secured to a pin 39 on the jaw thereby eliminating all jar to the parts. Both jaws are moved towards and away from the work by hydraulic means as follows. Bolted to the front of the base 17 is a vertical cylinder 40 in which is a double acting piston 41 mounted on a vertical piston rod 42. The cylinder 40 is provided with a reversing slide valve 43 manually operated by means of a rod 44. A port 45 leads to the top of the cylinder and a similar port 46 leads to the bottom thereof as will be hereinafter more fully described. The piston rod 42 has a rack 47 formed on one side, which rack meshes with a small pinion 48 on the shaft 49; a second pinion 50 on the shaft 49 meshes with a horizontal rack 51 secured to the under side of the slide 21. The pinion 48 is about half the size of the pinion 50, so that the slide 21 moves about twice as far as the piston 41, which allows for a rapid opening of the jaws. 100

As before stated, the jaw 22 is withdrawn by the slide 21 whereas the jaw 28 is withdrawn by gravity as the screw 32 is retracted through its connections with the slide 21. Both jaws are bifurcated to permit the use of a gauging device, such for instance as an Arnold gauge.

The piston 41 is operated by fluid pressure supplied by a suitable pump (not shown).

- 10 Said fluid passes along a pipe 52, through a throttling nipple 53 to a valve 54, thence through a pipe 55 to a vertical port 56 in the cylinder casting to the inlet chamber of the slide-valve 43 to either side of the piston at 15 the will of the operator. The exhaust passes out through a pipe 57 to the reservoir (not shown). A branch pipe 58 leads from the fluid pressure pipe 52 in advance of the throttling nipple 53 and enters a cylinder 59 which carries a control switch for the motor 20 that operates the revolving heads, all shown and described in a co-pending application No. 126,583, filed August 2, 1926. The throttling nipple 53 consists of a short length of pipe 25 having a small bore therethrough which allows the required pressure of fluid to reach the cylinder 40 without reducing the pressure to the various other devices which are supplied from the same source.

30 It will be obvious to those skilled in the art that various changes may be made in our device without departing from the spirit of our invention, and therefore we do not wish to limit ourselves to what is shown in the 35 drawings and described in the specification, but only as indicated in the appended claims.

Having thus fully described our said invention, what we claim as new and desire to secure by Letters Patent, is:

- 40 1. A hydraulic back-rest and support for cylindrical grinding machines comprising a base, a horizontal slide mounted on said base, a jaw pivoted to said base, a bushing slidable in said base, an adjusting screw mounted in 45 said bushing and coacting with said pivoted jaw, a bracket connecting said slide and bushing, a rack secured to the under side of said slide, a horizontal shaft beneath said slide and at right angles thereto, a large pinion on 50 said shaft meshing with said rack, a small pinion on the opposite end of said shaft, a vertical pressure cylinder secured to said casting, and a piston rod in said cylinder having a rack on one side to mesh with said small 55 pinion to rotate said shaft, substantially as set forth.

2. A combined back-rest and support for grinding machines comprising a base, a horizontal slide mounted on said base, an adjusting screw mounted in said slide to limit the movement thereof, a horizontally disposed movable bushing mounted in said base, an adjusting screw in said bushing for limiting the movement thereof, a bracket connecting said slide with said bushing for simultaneous

movement thereof, a bifurcated bearing block in said slide, a lever pivoted to said base and having a bearing block thereon, a depending lug on said lever adapted to coact with said last mentioned adjusting screw, a fluid pressure cylinder secured to said base, and rack and pinion connections from said cylinder to said slide to reciprocate the same, substantially as set forth. 70

3. A hydraulic back-rest and work support 75 for a crank grinding machine comprising a base, a back rest member slidable horizontally and transversely of the work, a support movable vertically, horizontally movable means mounted on said base for actuating 80 said movable members simultaneously and means to withdraw said movable means whereby work of widely varying diameters may be traversed past the work rest, substantially as set forth. 85

4. A hydraulic back-rest and support for crank grinders comprising a base, a longitudinal slide mounted on said base, a back-rest member mounted in said slide, a bushing slidable in said base, a vertical support member 90 mounted on said base, means carried by said bushing for operating said vertical support member, a bracket connecting said slide and said bushing and means to actuate said slide and bushing toward and away from the 95 work, substantially as set forth.

5. A hydraulic back-rest and work support for a grinding machine, comprising a base, a movable back-rest member, a movable support member, horizontally movable means 100 mounted on said base for actuating said movable members simultaneously, vertically movable means mounted on said base to actuate said horizontally movable means, and means to move said horizontally movable means 105 through a distance greater than the radius of the largest path described by the work piece, substantially as set forth.

6. In a grinding machine, a hydraulic back rest and work support comprising a base, a horizontal slide mounted on said base, a back rest member mounted in said slide, a bushing slidably mounted in the base, a work support pivotally mounted on said base and movable vertically by said bushing, means for 110 moving said slide and said bushing simultaneously comprising a cylinder, a piston in said cylinder, operable connection between said piston and said slide and bushing, means for diverting a portion of the operative fluid 115 from the high pressure fluid line of the grinding machine to the said cylinder, and means for restricting the flow of pressure fluid to said cylinder from said high pressure fluid line whereby operation of the back rest and work support will not materially affect the pressure in the high pressure fluid line of the grinding machine, substantially as set forth. 125

7. A hydraulic back rest and work support 130 for a machine of the kind described compris-

ing a base, a movable back rest member, a movable support member, horizontally movable means mounted on said base for actuating said movable members simultaneously, vertically movable means mounted on said base to actuate said horizontally movable means whereby a work piece may be traversed freely between said back rest and a grinding wheel, substantially as set forth.

10 In witness whereof, we have hereunto set our hands at Waynesboro, Pennsylvania this 18th day of October, A. D. nineteen hundred and twenty-six.

15 AMOS P. STEINER.
